CLAIM

(52) U.S. Cl.

The ornamental design for a top cap combined with front control for a door panel of a dish treating appliance, as shown and described.

USPC **D32/3**

(58) **Field of Classification Search**

DESCRIPTION

USPC D32/1, 2, 3, 54; D7/405
CPC A47L 15/4257; A47L 15/4293
See application file for complete search history.

FIG. 1 is a top perspective view of a top cap combined with front control for a door panel of a dish treating appliance showing our new design according to a first embodiment; FIG. 2 is a front view of the top cap combined with front control of FIG. 1;

FIG. 3 is a right side view of the top cap combined with the front control of FIG. 1, with the left view being a mirror image; and,

FIG. 4 is a top view of top cap combined with the front control of FIG. 1.

The broken lines in the figures illustrate the portions of the design that form no part of the claimed design.
